TREATING-OUT TRANSFORMER

Herbert A. Rose, Pittsburgh, Pa., assignor to
Westinghouse Electric & Manufacturing Company,
East Pittsburgh, Pa., a corporation of
Pennsylvania

Application December 21, 1932, Serial No. 648,204

8 Claims. (Cl. 175—363)

My invention relates to a treating-out transformer and particularly to a transformer having an auxiliary winding for initiating the current-carrying or main arcs in a rectifier being treated.

5 In treating-out rectifiers, it is desirable to provide sufficient voltage to supply the arc drop without any appreciable remainder in order to perform the operation economically.

However, in treating-out rectifiers, it is frequently found that a potential substantially equal to the arc drop is not sufficient to initiate a rectifying arc even in the presence of a continuously operating keep-alive arc. According to my invention, the treating out transformer is provided 15 with an auxiliary winding capable of producing a voltage sufficiently in excess of the arc voltage to "flash" the rectifier and start a rectifying arc, after which the rectifier may be switched back to the treating out winding for providing the normal 20 treating out current. Preferably the starting winding will be connected to only a portion of the anodes while the remaining anodes will remain connected to the treating-out winding.

Suitable switching equipment may be provided 25 for changing the connection to the treating out winding or the starting winding at the will of the operator. In order to provide an economical design, it is desirable that the starting winding be provided with a steep regulation characteristic 30 sufficient to reduce its voltage substantially to that of the treating-out winding when the starting winding is carrying current.

I have found that this auxiliary winding may be associated with the iron of the treating out 35 transformer or in some cases it may most advantageously be constructed as a separate transformer and then assembled as a unit with the main treating-out transformer.

Other objects and advantages will be apparent 40 from the following detailed description taken in conjunction with the accompanying drawings, in which

Figure 1 is a schematic view of a treating-out system embodying my invention.

45 Fig. 2 is a similar view showing a modification.

Fig. 3 is a graphic illustration of the potentials applied by the treating-out transformer, and

Fig. 4 is a view similar to Fig. 2 showing a modification according to my invention.

50 The treating-out transformer, according to my invention, comprises a suitable polyphase primary 1 adapted to be connected to the high tension line 2 by a suitable circuit breaker 3. As shown, the primary is connected in delta, each leg of the delta being comprised of two winding

groups and suitable variable connectors 4 between the groups for changing the number of turns in the delta windings, and consequently the voltage of the treating-out winding.

The secondary winding consists of a star connected group 6 adapted to be connected to the anodes 7 of the rectifier 8 undergoing treatment. A suitable keep-alive source 10 is provided for maintaining a keep-alive arc in the rectifier 8. A suitable current limiting resistor 12 is connected between the mid-point of the secondary winding 6 and the rectifier cathode 15. Preferably, the primary 1 is so adjusted that the voltage of the star secondary 6 is sufficient to supply the desired current to the anodes 7 at a voltage substantially equal the arc drop voltage of the rectifier. This prevents wasting of any material quantity of energy in the regulating resistor 12.

A suitable high voltage winding 20, preferably single phase, is associated with the primary 1 in such a manner that the terminal voltages of the auxiliary winding 20 may be connected to one or more of the anodes 7 of the rectifier 8. Suitable switches 21 may be provided for connecting the selected anodes either to the auxiliary starting 25 winding 20 or to the main treating-out winding 6.

A suitable connection 22 is provided between the mid-point of the treating-out winding 6 and the starting winding 20. The treat-out winding 6 may have a substantially flat voltage characteristic 30 on the different taps of the primary, as shown by the characteristic curves 25—26—27 of Fig. 3. However, the starting winding 20 should have a comparatively steep or drooping characteristic, as shown by the characteristic curve 30 in Fig. 3.

In the operation of my device, the keep-alive electrode 32 is energized by a suitable auxiliary rectifier 10, preferably connected by a suitable transformer 34 to the alternating current supply line 2. The breaker 3 is closed to connect the primary of the treat-out transformer to the alternating current line 2 and induce a suitable voltage in the secondary 6.

Usually it is found that this potential is not sufficient to establish a current-carrying arc between the anodes 7 and the cathode 15 even in the presence of the keep-alive arc. Two of the anodes 7 will then be disconnected from the treat-out winding 6 and connected to the starting winding 20. The high potential of this winding insures the formation of arcs to these anodes which readily causes "pick up" of the remaining anodes connected to the treat-out winding 6. After the anodes connected to the treat-out winding have picked up, the switches 21 may be operated to 55

connect the anodes originally connected to the starting winding to the treat-out winding.

The modification shown in Fig. 2 differs from that of Fig. 1 only in that the starting winding 40 is wound on a separate iron core and provided with its own primary winding 42. In some cases, it may be desirable to construct the starting winding for continuous operation and to connect it permanently to the starter anodes as shown at 45. The switch 21 between the anode lead and the treat-out transformer is used for connecting the anodes to the treat-out winding 6 to carry full current without disconnecting the same from the starting winding. The exceeding steep regulation 30 of the flashing winding will cause the current to divide between the starting winding and the treat-out winding in such proportion that the majority of the treat-out current will be supplied by the treat out winding 6.

20 The current supplied by the auxiliary winding 20 may be regulated if desired by a resistor arrangement 35 in the neutral connection 22.

A further modification (see Fig. 4) consists in utilizing the tank proper as the starting anode. 25 When the tank is used as the starting anode only one end of the auxiliary winding 50 can be connected to the tank while the other end must be attached to the cathode, thus the auxiliary winding 50 carries only unidirectional current. In 30 order to offset the saturating effect of the direct current in the secondary 50 the core 51 is provided with a suitable air gap 52.

35 While I have shown and described specific changes and modifications can be made therein without departing from the spirit and scope of my invention. I desire, therefore, that only such limitations shall be imposed as are embodied in the accompanying claims or as may be necessitated by the prior art.

40 I claim as my invention:

- 45 1. A treating out transformer for a vapor electric device comprising a primary winding, a poly-phase secondary winding adapted for connection to the anodes of the vapor electric device, said secondary winding having a terminal voltage substantially equal to the arc drop of the device, an auxiliary winding in said transformer, said auxiliary winding normally having a higher voltage than said secondary winding, means for selectively connecting two of the anodes to either said secondary or said auxiliary winding, and a common return connection to said secondary winding and said auxiliary winding.
- 50 2. A treating out transformer for a vapor electric device comprising a primary winding, a poly-phase secondary winding adapted for connection to the anodes of the vapor electric device, an auxiliary winding in said transformer, said auxiliary winding normally having a higher voltage than said secondary winding, means for selectively connecting two of the anodes to either said secondary or said auxiliary winding, a neutral tap in both said secondary and said auxiliary winding 55 and a resistor connected between said neutral

taps for limiting the current in said auxiliary winding.

3. In a rectifier system, a multi-anode rectifier, a transformer for treating out said rectifier comprising a main winding adapted for connection to the anodes, said winding being adapted to supply a voltage substantially equal to the arc drop of the rectifier, means for adjusting the voltage of the windings, an auxiliary winding associated with said transformer, said auxiliary winding being adapted to supply a voltage greater than the arc drop of the rectifier and means for connecting one of said anodes at will to said main winding or said auxiliary winding.

4. In a treating out device for a rectifier having a plurality of anodes, a polyphase transformer, phase windings in said transformer for attachment to said anodes, voltage adjusting taps in said transformer for adjusting the voltage applied to said anodes to a value substantially equal to the arc drop in the rectifier, an auxiliary winding associated with said transformer, said auxiliary winding having a steep regulation characteristic and means for connecting at least one of said anodes either to said phase windings or to 25 said auxiliary winding.

5. A treating out transformer for a mercury arc rectifier comprising a polyphase secondary having a neutral tap, means for connecting the secondary to the rectifier anodes, a tertiary winding in phase with one of the phases of the secondary winding, said tertiary having a steep regulation characteristic and means operable to disconnect an anode from the secondary and connect it to the tertiary.

6. A treating-out transformer for a vapor-electric device comprising, a winding adapted for connection to an alternating current line, a winding adapted for supplying to the anodes of a vapor-electric device a potential of the order of the 40 arc drop in the device, an auxiliary winding in said transformer adapted for connection to the anodes of the vapor electric device and means for limiting the current in said auxiliary winding.

7. A system for supplying treating-out current to a vapor-electric device comprising a winding adapted for supplying treat-out voltage to the anodes of the device being treated, a winding for producing a voltage in excess of the treating-out voltage, a switch for connecting at least one of the anodes of the device to either said first or said second winding and means for limiting the current supplied by said second mentioned winding.

8. A system for supplying treating-out current 55 to a vapor-electric device comprising a winding adapted for connection to the anodes of the device being treated, a winding for producing a voltage in excess of the treating-out voltage, a switch for connecting at least one of the anodes of the device to either said first or said second winding and resistance means for limiting the current supplied by said second mentioned winding.
